(57) CLAIM

The ornamental design for game device carrying case, as shown and described.

DESCRIPTION

FIG. 1 is a perspective view of a game device carrying case showing our new design;

FIG. 2 is a bottom plan view thereof;

FIG. 3 is a top plan view thereof;

FIG. 4 is a front elevational view thereof;

FIG. 5 is a rear elevational view thereof;

FIG. 6 is a left elevational view thereof;

FIG. 7 is a right elevational view thereof;

FIG. 8 is one perspective view showing the interior thereof;

FIG. 9 is another perspective view showing the interior thereof; and,

FIG. 10 is a top plan view showing the interior thereof.

The broken line showing of environment in the drawings is for illustrative purposes only and forms no part of the claimed design.
